DESIGN FOR A CASING FOR OIL BURNERS

John H. McIlvaine and Peter I. Hollman, Chicago,
Ill., assignors to McIlvaine Burner Corporation,
Chicago, Ill., a corporation of Illinois

Application June 12, 1935, Serial No. 57,244

Term of patent 14 years

To all whom it may concern:

Be it known that we, John H. McIlvaine and Peter I. Hollman, citizens of the United States, residing at Chicago, in the county of Cook and State of Illinois, have invented a new, original, and ornamental Design for a Casing for Oil Burner, of which the following is a specification, reference being had to the accompanying drawing, forming part thereof.

In the drawing:

Figs. 2 and 3 are a side and end view, respectively.

We claim:

The ornamental design for a casing for oil burner, substantially as shown.

JOHN H. MCILVAINE.

PETER I. HOLLMAN.
